SAFETY RAZOR

Leonard A. Young, Detroit, Mich.

Application January 2, 1936, Serial No. 57,098

6 Claims. (Cl. 30—50)

This invention relates to razors and has for its object to provide a razor and blade of improved cutting qualities, which will be adapted for more rapid assembly and disassembly, and which will provide for individual replacement of either or both of the dual cutting edges.

More particularly it is an object to provide a razor head comprising a clamp plate and a guard between which the blade or blades are held by a predetermined spring pressure thereby assuring exact positioning of the blades and a freedom from distortion such as is generally caused by an unduly large amount of holding pressure when this relation or pressure is determined manually.

Another object is to provide a blade of such shape that it is capable of flexing in its own plane and to so arrange the holding means therefore that such flexing is possible. This entails a clamping effect such that the blade depends for its impelling effect upon abutments rather than upon a high pressure clamping by its guard and end clamp.

Another object is to provide a construction comprising an end clamp and handle permanently secured together and to provide guards pivotally secured to the clamp, the guards being urged into blade clamping position by a spring acting against the guards mutually so that each receives identical pressure with the other.

Another object is to provide a pivotal connection between the handle and the head whereby the head may be swung to a position paralleling the handle. It may then be inserted into a narrower case.

A further object is to provide a handle having a drawer or magazine for the blades.

Other objects and advantages will become hereinafter more fully apparent as reference is had to the accompanying drawings wherein my invention is illustrated and in which—

Figure 1 is a front view of my improved razor with the handle partially broken away;

Fig. 2 is an endwise plan view of the razor;

Fig. 3 is a side elevation of the razor of Figure 1;

Figs. 4 to 7 are sections taken along the lines 4—4, 5—5, 6—6 and 7—7 respectively of Figure 1;

Fig. 8 is a section taken along the line 8—8

of Figure 2;

Fig. 9 is a view of a blade;

Fig. 10 is a front elevation of the razor and blade with one guard in blade releasing position;

Fig. 11 is a side elevation of the view of Figure 10, and

Fig. 12 shows the razor in position for insertion into a casing; and

Fig. 13 shows a modified handle.

More particularly I indicates a razor handle equipped with a drawer 2 for retaining blades 3, 5 pending use. Pivoted secured to the handle I is an end clamp 4 having brackets 5 at each end thereof and a central depending member or post 6 integral therewith. The handle and end clamp may be secured together as illustrated without the use of a bolt, thereby making a neat joint. Through the post 6 and brackets 5, a pin 7 is inserted to constitute a hinge pin for individually pivoted guards 8 which are notched or serrated at 9, as is conventional practice. One or more springs 10 are secured to the pin 7 with its ends pressing upwardly to urge each of the guards 8 towards the clamp plate. With the spring 10 of coil type and wrapped loosely around the pin 7 it is evident that the guards 8 will each be subjected to identical pressures.

In order to open the guards 8 with respect to the end clamp 4, I provide thumb rests 11. When a guard is depressed into the position shown in Figs. 10 and 11, the blade 3 may be placed in position and upon release of the thumb rest the blade is then held with the pressure dictated by the spring 10.

The blade 3 is preferably made exactly as shown with the width at the outer edges being sufficient to expose its cutting edge into cutting position and its rear edges 12 abutting against the brackets 5. The ears 13 project outwardly to constitute both a part of the abutment means and as a means for grasping the blade for insertion and removal. Between the end portions 13 the rear edge is decidedly curved so that the midportion is of very little greater width than the tapered cutting edge. This will give a flexibility in the plane of the blade because of this shape and because the blade is held by a predetermined spring pressure. In other words the clamping effect is only sufficient to hold the blade in position but not enough to interfere with flexibility of the blade in its plane because the force exerted by the hand of a user is transmitted through the brackets 5 to the rear edges 12 rather than through the body of the blade. This, of course, is true for both blades 3 as the construction and arrangement of the two guards 8, each of which has a separate blade 3, is identical and the shape of both blades 3 is identical. By this construction the blade may be uniformly tempered which is not possible with conventional blades because with a wide blade if the center is tempered similarly to the cutting

edge it will fracture under clamping pressures. This blade is therefore considerably cheaper to manufacture while retaining highest quality.

When the razor is not in use, the head comprising the end clamp 4 and both guards may be tilted to the position illustrated in Fig. 12 for insertion into a casing 14. The blades do not need to be removed.

As shown in Fig. 13, the drawer 2 may be omitted and the extra blades stored in the hollow handle which is provided with an end closure cap 15.

What I claim is:—

1. A razor comprising a handle, a blade seat member extending transversely of said handle opposite an end thereof, dual blade guards pivotally mounted upon said member to swing toward and from the seat side thereof, and spring means common to both of said guards for urging said guards toward said member with equalized pressures to clamp a blade between said member and guards.

2. A razor comprising a handle, a blade seat member pivotally secured to said handle, a blade on each side of said handle each in pivotal relation with said member and said handle, and spring means for urging said guards towards said member.

3. A razor comprising a handle, an end blade seat member pivotally secured to one end of said handle to swing transversely to said end, dual blade guards pivotally mounted between said handle and member, and spring means for urging

said guards toward said member to clamp a blade therebetween.

4. A razor comprising a handle, a blade seat member on said handle for the seating of a blade thereagainst, a pivot means extending longitudinally of said member, dual blade guards pivotally mounted on said pivot means, and a spring attached to said pivot means having its ends in pressure contact with said blade guards for urging said guards toward said seat member.

5. A razor comprising a handle and an end member for the seating thereagainst of a blade, said end member having a hinge pin bracket depending from each end thereof, a hinge pin carried by said brackets, dual blade guards pivotally secured to said hinge pin to swing thereon at opposite sides thereof toward and from said member, and means for urging said guards toward said end member to clamp the blade therebetween.
